AIR CUSHION VEHICLE

Jean Bertin, Neuilly-sur-Seine, France, assignor to
Societe d'Etudes et de Development des Aero-
glisseurs Marins SEDAM, a corporation of France

Filed Oct. 7, 1968, Ser. No. 13,864

Claims priority, application France Apr. 5, 1968

Term of patent 14 years

Int. Cl. D12—06

U.S. Cl. D71—1

Fig 1

Fig 2

Fig 3

Fig 4

FIGURE 1 is a plan view of a design of an air cushion vehicle according to the invention.

FIGURE 2 is a side elevational view of the vehicle of FIGURE 1.

FIGURE 3 is a rear elevational view of the vehicle of FIGURE 1.

FIGURE 4 is a front elevational view of the vehicle of FIGURE 1.

I claim:

The ornamental design for an air cushion vehicle, as shown.
